UNITED STATES PATENT OFFICE.

MORTON DECKER, OF CHICAGO, ILLINOIS, AND MARVIN H. MATTY, OF CLAYTON, NEW YORK.

CREAM-SEPARATOR.

No. 880,866.

Specification of Letters Patent.

Patented March 3, 1908.

Application filed June 28, 1906. Serial No. 323,849.

To all whom it may concern:

Be it known that we, MORTON DECKER and MARVIN H. MATTY, both citizens of the United States, residing, respectively, at Chicago and Clayton, in the counties of Cook and Jefferson, and States of Illinois and New York, have invented certain new and useful Improvements in Cream-Separators; and we do hereby declare the following to be a full, clear, and exact description of the invention, such as will enable others skilled in the art to which it appertains to make and use the same.

Our invention relates to improvements in cream separators, and more especially to driving mechanism therefor.

The object of our invention is to provide a simple driving mechanism for a cream separator with the gearing contained in a removable gear case permitting the use of a sprocket chain drive inside the casing with a low down milk supply tank, whereby the milk may be readily fed into the top of the bowl.

With these objects in view, our invention consists in the construction and combination of parts as hereinafter described and claimed.

In the accompanying drawings; Figure 1 is a side view of our improved invention. Fig. 2 is a similar view with the frame and gear casing shown in section. Fig. 3 is a side view of the removable gear case, and Fig. 4 is an end view of the same.

a represents the supporting frame, which consists of a hollow metal casting elliptical in its general outline, and adapted to be fastened by bolts *b* to the floor, or other suitable support. The top of this frame is closed by a removable cover *c*. In the top of the frame *a* is journaled a shaft *d*, which is provided with a driving crank *e*, and on the shaft *d* is mounted a sprocket wheel *f*, over which a sprocket chain *g* passes, said chain also passing over a small sprocket wheel *h* journaled on a shaft *i* on the removable gear casing *j*. This removable gear casing is shown detached in Fig. 3. It is of such a size as to extend nearly across the frame *a*, and is provided with a boss *k*, which is adapted to enter a perforation in the frame *a*. This boss is screw threaded for the reception of a headed screw *m*, and when this screw is turned home the gear case is firmly held in the frame *a*, a flange *n* being provided, which fits against the side of the frame *j*. The upper part of the gear casing is provided with a removable

cover *o*, which cover is provided with a flange *p* fitting down within the main portion of the gear case, and held in place by the frame *a* when the gear case is inserted in said frame. On the shaft *i*, which carries the sprocket wheel *h*, is journaled a gear wheel *q*, which meshes with a small gear wheel *r*, on the shaft *s*, journaled in the gear casing. The shaft *s* carries a larger gear wheel *t*, which engages with the spirally arranged gear *u* on the shaft *v* of the separator proper. A nut *w* on the lower end of the shaft *v* keeps the latter in place. The separator bowl *x*, provided with the cream and milk pipes *y* and *z*, is supported in any suitable way, as by an anti-friction ball bearing in the casing *1* attached to the side of the frame *a*.

2 represents an automatic oiling device, which supplies oil to the separator bearing, which oil drips down the spindle *v*, thus affording a means for oiling the gears in the case *j*. The gear wheels are thus thoroughly lubricated as they throw the oil from one to the other, the cover *o* serving to keep the oil from being thrown out of the gear case.

3 represents the metallic can, which communicates by means of a pipe *4* with the top of the separator *x*. The spindle *v* is so arranged that it can be easily detached from the separator, and after it has been so detached and the sprocket chain *g* disengaged from the sprocket wheel *h*, the whole gear case *j* containing the driving gear can be readily removed from the frame *a* for the purpose of cleaning or adjustment, and as readily replaced.

The construction described has the further advantages that the sprocket chain *g* is completely covered when in use, thus avoiding liability of accidents, and the milk can *3* can be made low down and located close to the separator, feeding into the top thereof.

Having thus described our invention, what we claim as new and desire to secure by Letters Patent of the United States, is:—

1. The combination of a hollow metal casting provided with oppositely placed openings of different sizes, a separator supported by said casting, a removable gear casing containing the driving gear for said separator, said gear casing being provided with a projection for engaging the smaller opening in said casting and with a shoulder adapted to fit against said casting, said gear casing being adapted to be slipped into the larger opening in said casting, means for securing

said gear casing in said casting, and means for operating the gearing in said casing, substantially as described.

2. The combination of a hollow metal casting provided with two openings of different sizes placed opposite to each other, a removable casing carrying the driving gear and provided with a shoulder and a projection, means for fastening said gear casing in said casting, a separator supported on said casting and provided with a spindle removably connected thereto and carried by said gear casing, a milk can supported by said casting at a higher level than said separator, and means for operating the gear in said removable gear casing, substantially as described.

3. The combination of a supporting frame consisting of a hollow metal frame, provided with a large opening and a small opening placed opposite each other, a removable cover for said casting, a separator supported by said frame, a removable casing containing the driving gear for said separator, said casing being provided with a projection adapted to fit into the smaller opening in the supporting frame, and said casing being also adapted to

be slipped into the larger opening in said frame and having a shoulder adapted to fit against said frame, a headed screw adapted to fit into the projection on said gear casing and with the aid of said shoulder to hold said casing rigidly in position in relation to said frame, a sprocket wheel on the outside of said gear casing, an operating crank, a sprocket wheel operated by said crank, a sprocket chain connecting said sprocket wheels, and a milk can supported by said frame at a higher level than said separator, said separator being provided with a detachable spindle, which spindle is carried by said gear casing, substantially as described.

In testimony whereof, we affix our signatures, in presence of witnesses.
